RURAL MAIL BOX

Charles A. Masso, Erie, Pa.

Application November 7, 1957, Serial No. 48,363

Term of patent 14 years

(Cl. D74—9)

FIG. 1

FIG. 3

Fig. 1 is an isometric view of a rural mail box embodying my new design as it appears in open position;

Fig. 2 is another isometric view thereof as it appears in closed position; and

Fig. 3 is a side elevational view thereof.

The back end of the mail box is plain and the side opposite to the side shown is similar to the side shown; however, no flag appears on the opposite side.

I claim:

The ornamental design for a rural mail box, as shown and described.
